UNITED STATES. PATENT OFFICE.

J. HENRY MORRISON AND CLINTON L. ALLEN, OF NORWICH, CONN., ASSIGNEES
TO THE ALLEN SPOOL AND PRINTING COMPANY, OF SAME PLACE.

AUTOMATIC BORING-MACHINE.

SPECIFICATION forming part of Letters Patent No. 361,832, dated April 26, 1887.

Application filed September 21, 1885. Serial No. 177,669. (No model.)

To all whom it may concern:

Be it known that we, J. HENRY MORRISON and CLINTON L. ALLEN, both of the city of Norwich, county of New London, and State of Connecticut, have invented certain new and useful Improvements in Automatic Boring-Machines, which improvements are fully set forth and described in the following specification, reference being had to the accompanying drawings.

Our improvements relate to a new combination of mechanical devices by means of which spool-blanks, braid-rolls, or other analogous articles of uniform size and shape are fed or moved, one by one, to a given place, where they are firmly held while a drill or bit advances and bores a hole in or through them. As the drill recedes the holding mechanism releases said bored blank and another blank takes its place and is properly clamped before the drill again advances.

In the annexed drawings, Figure 1 is an end elevation of our improved boring-machine, and Fig. 2 a side elevation of the same. Fig. 3 is an enlarged view, partly in section, showing the clamping mechanism employed to hold the blanks while in the act of boring, and also illustrates the means which we have provided to adjust said mechanism to hold blanks of greater or less diameter. Fig. 4 is a detached top view of the adjustable feed-trough; Fig. 5, a detached view of the inner forked end of arm *n* and its operating-cam; and Fig. 6 is a top detached view of the arm *f*, which, reaching around the feed-trough, carries the cut-off plate *e*.

A represents the bed of our machine, supported by standards *B B'*. At a convenient point below the bed *A* is a shaft, *C*, having bearings in the standards *B B'*, and kept in continuous rotary motion by a driving-pulley, *D*. Bolted to the bed *A* are uprights *a*, having secured to their upper ends, or formed as an integral part of the same casting, a horizontal frame, *b*, said frame being located immediately over the mechanism which receives and clamps the blank about to be bored. Secured to this supporting-frame *b* by right-angular slotted lugs 1 2 3 4 are vertical guide-strips *c c' c'' c'''*, which form the walls of the feed chute or trough. Strip *c* may, if pre-

ferred, be rigidly attached to frame *b*, but strips *c'*, *c''*, and *c'''* are secured adjustably to said frame, in order that they may be moved backward or forward to receive larger or smaller blanks, as the case may be. The feed-trough thus provided is kept filled with blanks, either by the operator in charge of the machine or by a suitable automatic feeder, into whose hopper the blanks are poured in bulk and from which they drop into the trough as the line of blanks descends in said trough. The blanks, as they move downward by gravity in the trough, come in contact with and are checked by a plate, *e*, which is secured adjustably to and moves with the clamping-block *E*. This clamping-block has secured to its upper side a metallic frame, *f*, which, extending around the feed-trough, carries a plate, *h*, provided as a cut-off, so that but one blank can leave the trough at each complete movement of the clamping-block *E*.

Block *E* has a transverse movement (in suitable ways or guides) on bed *A*, stopping in the position seen in Fig. 3 while a blank is being bored, then receding to allow the bored blank to drop out of the way and allow another blank to drop into place to be bored.

As the block *E* recedes the cut-off plate *h* passes under the line of blanks, supporting them in the trough until block *E* again advances, when the line of blanks moves downward in the trough until the lowest blank rests on the stop-plate *e*, having traveled a distance equal to the diameter of a single blank. Thus it will be seen that the two plates *e* and *h*, working in unison with the block *E*, release a single blank at each forward and backward movement.

Pivoted in the outer end of the clamping-block *E* is a lever-arm, *g*, whose lower end is pivoted in a bracket secured to one of the braces or girders which bind together and stiffen the machine-frame.

Screwed in bed *A* at a point opposite to the arm *g* is a machine-screw, *h*, whose head forms an adjustable stop against which arm *g* impinges, the forward movement of said arm being limited by the position of said screw-head.

In Fig. 1 we have shown a double machine—that is to say, a machine with duplicate mech-

anism placed side by side on the same supporting-frame, but operated by a single central driving-shaft and a single series of cams. In such a form the lever-arm *g* and its mate *g'*, 5 on the opposite side, are connected by a stiff spiral spring, *p*, which acts with a constant tendency to draw said lever-arms inward. In a single machine the inner end of said spring would be secured to the machine-frame.

10 Pivoted to arm *g*, at or near its central portion, is a rod, *n*, whose inner end is forked and straddles shaft *C*, the arms of the fork being somewhat longer than the desired movement of rod *n*. This forked piece *n* has on 15 one side a small pulley, *o*, which rides on the periphery of cam *I*, and is moved outward by each revolution of said cam. It will now be understood that as shaft *C* revolves cam *I* will force the forked rod *n* and arm *g* outward, said 20 arm carrying with it the clamping-block *E* and the cut-off mechanism above described, and as cam *I* continues its round, spring *p* acts to move said parts (forked rod, arm *g*, and clamping mechanism) inward again.

25 As a further means for holding a blank while being bored, we have provided a rod, *H*, sliding in suitable bearings and held forward against the end of the blank by a spiral spring, *r*, with a tendency to straighten up each blank 30 and hold its face at right angles with the drill. To move rod *H* and release the bored blank, we use an arm, *K*, hinged at its lower end and having on one side a friction-pulley which engages cam *m* on the shaft *C*, said cam being so 35 timed relative to the other movable elements that it acts to move rod *H* outward as the drill recedes.

Having thus described the feeder and clamping parts and the devices which move them, we 40 will now proceed to describe the reciprocating drill-arbor *N*, which has a sliding movement in bearings forming, practically, a part of bed *A*, and is kept in continuous rotary motion by the belt *P* and pulley *Q*.

45 On arbor *N* is a collar, *t*, having trunnions which engage the forked end of lever-arm *R*, said arm being pivoted at its lower end to a frame supported by rods *u*. Pivoted in arm *R*, at a point opposite shaft *C*, is a friction- 50 pulley, *v*, which rests on cam *S*. Within the bed *A* is a strong spiral spring, *w*, one of whose ends is made fast to said bed, the other end being connected to arm *R*, near its free end. When in operation, spring *w* holds pulley *v* 55 against the face of cam *S*, and said cam at each revolution forces arm *R* and drill-arbor *N* outward, or away from the bored blank, acting against the force of spring *w*. The clamping-block *E* has on the upper side of its inner 60 end a longitudinally-adjustable piece, *E'*, said piece being adjusted by means of screw *y* in arm *f*, and when properly adjusted is securely clamped to the block *E* by a screw or bolt, 12. The inner end of said adjustable piece *E'* unites 65 with the inner end of clamping-block *e* to form a holding-surface, substantially V-shaped, and it will be seen that when said piece is prop-

erly adjusted in connection with the vertical adjustment of the stop-plate *e* (as referred to below) blanks of various diameters may be securely clamped. The opposite side of the blank rests against a rectangular block, *T*, which is held rigidly in gibbed ways, being adjusted to the desired position by a nut, 5, on a screw, 6, whose head impinges against an upward extension, 7, on the bed *A*. The stop-plate *e* is so secured to the clamping-block *E* that when its binding-screw is loosened said plate may be lowered to accommodate blanks of larger diameter, the plate proper preserving at all times a horizontal position, but moving diagonally. Inasmuch as there is a possibility of a blank becoming wedged or blocked within the holding mechanism, we have provided safety-joints in arms *g* and *R*, so that if 85 a blank should fail to drop after being bored no injury could come to the machine. This safety device consists of a joint in said arms *g* and *R* at 8, said joint being kept closed so long as the machine works perfectly by a spring, 9, one of whose ends is secured to the main arm, and the other end fastened to a right-angular arm, 10, formed as a part of the shorter portion of said arms *g* and *R*. So long as the machine continues to work perfectly the jointed 95 arms *g* and *R* are each practically a single piece; but should a blank become wedged, so that the holding-block *E* and cut-off cannot move outward to their proper positions, the springs 9 yield, allowing the joints above referred to to open, as shown in dotted lines in Figs. 1 and 2.

The action of our machine when in use is as follows: As shaft *C* rotates cam *I* causes arm *g* and block *E* to move, allowing a single 105 blank to drop into place to be bored, as in Fig. 3. The rod *H* now moves forward against the end of said blank, being held forward by spring *r*. At the instant the blank is thus firmly secured the drill advances, bores a hole, 110 and recedes, when rod *H* is moved outward by cam *M*, and the clamping-block *E* is moved to release the finished blank and admit a new one.

What we claim as new, and wish to secure 115 by Letters Patent, is—

1. In combination with a feed-trough substantially of the form described, a transversely-movable clamping-block located at the discharge end of said trough, having secured 120 thereto and adapted to move therewith a stop-plate, *e*, to limit the downward movement of the blank about to be bored, and a cut-off plate, *h*, to check the line of blanks in said trough when the clamping device is opened, said cut-off plate being placed on the opposite side of the trough from the clamping-face of the said movable block when the parts are in clamping position, all being substantially as herein described, and for the objects set forth. 125

2. In a suitable supporting-frame, in combination with a continuously-rotating reciprocating arbor and drill, a feed-trough whose discharge end is located in the path of said 130

drill, and a checking, clamping, and releasing device having both the cut-off plate *h* and stop-plate *e*, secured to and adapted to move with the movable section of the clamp, said cut-off

5 plate being placed on the opposite side of the trough from the clamping-face of the movable section when the parts are in clamping position and above the level of the stop-plate a distance equal to the diameter of a single blank, 10 substantially as herein described, and for the objects set forth.

3. In combination with a feed-trough substantially of the form described and a transversely-movable clamping-block located and 15 constructed as set forth, a lever-arm formed of two hinged sections, *g* 10, held normally in a closed position by spring 9, the free end of the complete lever-arm thus formed being connected with the said transversely-movable 20 clamping-block in the manner and for the object specified.

4. A continuously-rotating reciprocating drill-arbor and drill, a feed or conducting trough, substantially as described, and the 25 clamping-block *E*, having secured adjustably to it plates *e h*, said clamping-block being moved forward and backward intermittently

by lever-arm *g*, forked arm *n*, spring *p*, and the continuously-rotating cam *I*, all of said parts being combined and used substantially 30 as and for the purpose specified.

5. In combination with a reciprocating drill-arbor and drill and a suitable feed-trough, the clamping-block *E*, mechanism for cutting off the line of blanks, an adjustable abutting block, 35 *T*, and the stop-plate *e*, so secured to the block *E* that it may be raised or lowered to support blanks of greater or less diameter, substantially as described.

6. In combination with a reciprocating drill- 40 arbor and drill and a suitable feed-trough, the clamping-block *E*, having secured adjustably thereon the auxiliary block or slide *E'*, mechanism for cutting off the line of blanks, an adjustable abutting block, *T*, and the stop-plate 45 *e*, so secured to the block *E* that it may be raised or lowered, all substantially as and for the objects set forth.
